ELECTRICAL IGNITION APPARATUS FOR
INTERNAL COMBUSTION ENGINES

Frank Raymond Faber Ramsay, London, England, assignor to D. Napier & Son Limited, London, England, a company of Great Britain

Application January 10, 1938, Serial No. 184,310
In Great Britain January 20, 1937

10 Claims. (Cl. 123—169)

This invention relates to electrical ignition apparatus for internal combustion engines and of the kind in which means are provided tending to prevent the electrical ignition apparatus causing interference with wireless receiving apparatus used, for example, on the aeroplane or other vehicle on which the internal combustion engine is installed.

It has been proposed for the purpose of preventing interference with wireless receiving apparatus to interpose a resistance of the order of 10,000 ohms between the end of each high tension sparking plug lead and the sparking plug terminal. This proposal only partially prevents interference and in an alternative arrangement for preventing interference more completely, a completely screened high tension system is employed, that is to say the whole of the high tension circuit including the high tension sparking plug cables, the central electrodes of the sparking plugs and other parts through which the high tension current flows, are enclosed in a continuous metallic screen which is earthed, that is to say connected to the body of the engine.

This latter expedient, however, tends to cause rapid erosion of the sparking plug points due, it is believed, to the fact that the earthed screen and the high tension cables together form in effect a condenser which gives to the circuit the character of an oscillating circuit, and the object of the present invention is to overcome this difficulty and thus not only provide elimination of interference which radio signals but also prevent the rapid erosion of the sparking plug points.

To this end, according to the present invention, a resistance is provided between each high tension cable and its associated sparking plug point in completely screened electrical ignition apparatus for an internal combustion engine.

The value of the resistance may vary but is preferably between 100 ohms and 4,000 ohms and in most cases should be of the order of 1,000 or 1,500 ohms.

In any case this resistance may either be disposed between the end of the cable and the sparking plug terminal or may be disposed within the sparking plug insulator between the sparking plug terminal and the appropriate sparking plug point.

An arrangement according to the invention is illustrated diagrammatically in Figure 1 of the accompanying drawing while Figure 2 shows partly in cross-section a constructional arrangement incorporating a resistance according to the invention between a screened high tension cable and a sparking plug.

In the circuit according to the invention shown in Figure 1, A is the secondary winding of the transformer of the magneto or coil type ignition apparatus of which A¹ is the primary winding, one end of the secondary winding A being connected as usual to earth, that is to say to the body of the engine, which is represented by the conductor B. The other end of the secondary winding is connected as usual to the arm C of a distributor C¹ the various terminals of which are connected respectively to the central electrodes of the sparking plugs of the various cylinders. In Figure 1 the distributor is shown as having six such terminals for use with a six-cylinder engine and for the sake of simplicity the high tension cable leading from only one of such terminals to its associated sparking plug is illustrated. In practice each terminal of the distributor would be connected to its associated sparking plug in the manner shown for one terminal. Thus, each terminal of the distributor is connected to one end of a high tension cable D the other end of which is connected through a resistance D¹ of, say, 1,000 ohms to the central electrode E of the sparking plug F the body F¹ of which is, as shown, connected to earth by being screwed into its appropriate cylinder. The high tension circuit is completely screened in known manner, this screening representing a capacity indicated at G.

It will be appreciated that the screening is earthed and encloses also the insulator and the part of the central electrode of the sparking plug lying above the body F¹ thereof and Figure 2 shows one way in which the resistance may be arranged.

In the arrangement shown in Figure 2, the high tension cable D with the usual rubber or like insulation D² is screened also in known manner by a woven metallic sheath D³. The end of this cable adjacent to the sparking plug passes into an L-shaped connector comprising an outer metallic casing G containing a filling of moulded insulating material G¹. One arm of the metallic casing G is externally screwthreaded, as shown at G², where it is engaged by a screwthreaded collar G³ serving to clamp to the casing G a flange G⁴ soldered or similarly connected to the sheath D³. The high tension cable D with its surrounding insulating material D² passes into a bore in the filling of insulating material G¹, the cable itself projecting from the end of its insulation and having a nipple H attached thereto. The nipple, which is of ball-like form, lies within a three-sided spring clip J the sides of which press thereon so as to make close electrical contact.

contact therewith and the resistance D^1 is disposed in a bore in the filling G^1 at right angles to that into which the high tension cable D projects. The lower end of the resistance D^1 is acted upon by a cap K against which bears one end of a spring K^1 the other end of which bears on a cap K^2 , the caps K and K^2 being capable of sliding longitudinally within a tubular surrounding sheath K^3 and the arrangement being such that the spring K^1 acts through the cap K to press the resistance D^1 upwards so that its upper end makes close contact with the lower face of the spring clip J .

The device is intended for use with a sparking plug F^1 of the known type shown in which a metallic screening member F^2 lined with insulating material F^3 extends upwards from the body F^1 of the plug and is externally screwthreaded at its upper end to be engaged by a screwthreaded collar L serving to draw a flange G^5 on the metallic casing G downwards into close contact with the upper end of the screen F^2 .

The filling G^1 of insulating material extends downwards beyond the flange G^5 , as shown, and the arrangement is such that when the device is applied to a sparking plug as shown, the central electrode E of the plug engages the lower cap K^2 and presses it upwards somewhat against the action of the spring K^1 . Thus the spring K^1 not only maintains the resistance D^1 in close contact with the spring clip J but also serves to carry high tension current between the resistance D^1 and the central electrode E of the sparking plug F^1 .

With this construction it will be seen that complete metallic screening is provided for the high tension conductor, this screening extending downwards around the resistance D^1 and the insulator and central electrode E of the sparking plug to the body F^1 of the sparking plug which is connected to earth.

It is to be understood that the construction adopted to provide for the interposition of the resistance between the high tension lead and the central electrode of the sparking plug may vary within wide limits according to requirements, the type of sparking plug or screening employed, the space which is available for the connection between the high tension lead and the central electrode of the sparking plug and other requirements. Further, if desired the resistance may be arranged in the length of the high tension lead within the screening, or may be arranged within the insulator of the sparking plug or an extension of this insulator.

What I claim as my invention and desire to secure by Letters Patent is:

1. Electrical ignition apparatus for internal combustion engines, including at least one high tension cable, a sparking plug to which one end of the cable is connected, a source of high tension current to which the other end of the cable is connected, a continuous earthed metallic screen enclosing the high tension circuit, and a resistance of between 100 and 4,000 ohms interposed between the high tension cable and the sparking plug point.

2. Electrical ignition apparatus for internal combustion engines, including at least one high tension cable, a sparking plug to which one end of the cable is connected, a source of high tension current to which the other end of the cable is connected, a continuous earthed metallic screen enclosing the high tension circuit, and a resistance of between 500 and 1,500 ohms inter-

posed between the high tension cable and the sparking plug point.

3. Electrical ignition apparatus for internal combustion engines including at least one high tension cable, a source of high tension current to which one end of the cable is connected, a sparking plug, a continuous earthed metallic screen enclosing the high tension circuit, and means including a resistance of between 100 and 4,000 ohms for connecting the other end of the high tension lead to the outer end of the central electrode of the sparking plug.

4. Electrical ignition apparatus for internal combustion engines including at least one high tension cable, a source of high tension current to which one end of the cable is connected, a sparking plug, a continuous earthed metallic screen enclosing the high tension circuit, and means including a resistance of between 1,000 and 1,500 ohms for connecting the other end of the high tension lead to the outer end of the central electrode of the sparking plug.

5. Electrical ignition apparatus for internal combustion engines including at least one high tension cable, a source of high tension current to which one end of the cable is connected, a sparking plug, a metallic screen for the high tension cable and means for connecting the other end of the cable to the sparking plug comprising a coupling member including a metallic casing, a filling of insulating material within the casing having a bore therethrough, means for clamping one end of the casing to the end of the cable screen, means for connecting the other end of the casing to a metallic body which screens the central electrode of the sparking plug, a resistance of between 100 and 4,000 ohms within the bore of the filling, means for connecting one end of the resistance electrically to the high tension cable, and means for connecting the other end of the resistance electrically to the central electrode of the sparking plug.

6. Electrical ignition apparatus for internal combustion engines including at least one high tension cable, a source of high tension current to which one end of the cable is connected, a sparking plug, a metallic screen for the high tension cable and means for connecting the other end of the cable to the sparking plug comprising a coupling member including a metallic casing, a filling of insulating material within the casing having a bore therethrough, means for clamping one end of the casing to the end of the cable screen, means for connecting the other end of the casing to a metallic body which screens the central electrode of the sparking plug, a resistance of between 500 and 1,500 ohms within the bore of the filling, means for connecting one end of the resistance electrically to the high tension cable, and means for connecting the other end of the resistance electrically to the central electrode of the sparking plug.

7. Electrical ignition apparatus for internal combustion engines including at least one high tension cable, a source of high tension current to which one end of the cable is connected, a sparking plug, a metallic screen for the high tension cable and means for connecting the other end of the cable to the sparking plug comprising a coupling member including a metallic casing, a filling of insulating material within the casing having a bore therethrough, means for clamping one end of the casing to the end of the cable screen, means for connecting the other end of the casing to a metallic body which screens the

5 central electrode of the sparking plug, a metallic member within the bore in the filling to which the end of the high tension cable is electrically connected, a resistance of between 100 and 4,000 ohms arranged in this bore with one end engaging this metallic member, a spring within the bore one end of which acts on the other end of the resistance to press it into contact with the metallic member, and a contact member acted upon by the other end of the spring and adapted 10 to engage the end of the central electrode of the sparking plug.

15 8. Electrical ignition apparatus for internal combustion engines including at least one high tension cable, a source of high tension current to which one end of the cable is connected, a 20 sparking plug, a metallic screen extending from the metallic body of the sparking plug around the insulator thereof, and a connector for coupling the high tension cable to the sparking plug comprising a metallic casing, a filling of insulating material within the casing having a bore therethrough, means for clamping one end of the casing to the end of the cable screen, means 25 for connecting the other end of the casing to a metallic screen surrounding the insulator of the 30 sparking plug, a resistance of between 100 and 4,000 ohms within the bore of the filling, means for connecting one end of the resistance electrically to the high tension cable, and means for connecting the other end of the resistance electrically to the central electrode of the 35 sparking plug.

9. A connector for coupling a screened high tension cable in the ignition circuit of an internal combustion engine to a sparking plug comprising a metallic casing, a filling of insulating material within the casing having a bore therethrough, means for clamping one end of the casing to the end of the cable screen, means for connecting the other end of the casing to the metallic body of the sparking plug, a resistance of between 100 and 4,000 ohms within the bore in 10 the filling, means for connecting one end of the resistance electrically to the high tension cable, and means for connecting the other end of the resistance electrically to the central electrode of 15 the sparking plug.

10. A connector for coupling a screened high tension cable in the ignition circuit of an internal combustion engine to a sparking plug comprising a metallic casing, a filling of insulating material within the casing having a bore therethrough, 20 means for clamping one end of the casing to the end of the cable screen, means for connecting the other end of the casing to the metallic body of a sparking plug, a resistance of between 500 and 1,500 ohms within the bore in the filling, 25 means for connecting one end of the resistance electrically to the high tension cable, and means for connecting the other end of the resistance electrically to the central electrode of the 30 sparking plug.
